CLAIM

We claim the ornamental design for a golf club shaft, as shown and described.

DESCRIPTION

FIG. 1 is a front perspective view of a golf club shaft.
FIG. 2 is an enlarged front elevational view of the golf club shaft, the broken away section is shown for ease of illustration.

FIG. 3 is a butt-end view of FIG. 2; and,
FIG. 4 is the opposite end view of FIG. 3.

The broken line showing of grip and golf club head is for illustrative purposes only and forms no part of the claimed design.
